UNITED STATES PATENT OFFICE.

JESSIE ARMSTRONG HELMAN, OF CHICO, CALIFORNIA, ASSIGNOR TO ANNA F. DESMOND, OF LOS ANGELES, CALIFORNIA.

DESIGN FOR AN INCENSE-BURNER.

6,362.

Specification for Design.

Patented Oct. 5, 1920.

Application filed January 12, 1920. Serial No. 351,058. Term of patent 7 years.

To all whom it may concern:

Be it known that I, JESSIE ARMSTRONG HELMAN, feme sole, a citizen of the United States, residing at Chico, in the county of Butte and State of California, have invented a new, original, and ornamental Design for an Incense-Burner, of which the following is a specification, reference being had to the accompanying drawing, forming part thereof.

I claim:

The ornamental design for an incense burner, as shown.

JESSIE ARMSTRONG HELMAN.

Witnesses:

FREDERICK J. ROSE,
ELLENORE K. ROBBINS.
